UNITED STATES PATENT OFFICE.

JOHN EMERSON SCOTT, OF MARBLEHEAD, MASSACHUSETTS, ASSIGNOR TO UNITED SHOE MACHINERY COMPANY, OF PATERSON, NEW JERSEY, A CORPORATION OF NEW JERSEY.

UPPER-PULLING APPARATUS.

1,049,539.

Specification of Letters Patent.

Patented Jan. 7, 1913.

Application filed July 7, 1910. Serial No. 570,790.

To all whom it may concern:

Be it known that I, JOHN EMERSON SCOTT, a citizen of the United States, residing at Marblehead, in the county of Essex and 5 State of Massachusetts, have invented certain Improvements in Upper-Pulling Apparatus, of which the following description, in connection with the accompanying drawings, is a specification, like reference characters on the drawings indicating like parts in the several figures.

This invention relates to apparatus for use in the manufacture of boots and shoes and particularly to upper pulling devices. 15 It is herein shown for the purpose of exemplification as embodied in a hand pincer of the type used by workmen in connection with the lasting and pulling-over operations.

In stretching an upper and drawing it inwardly over the shoe bottom there is always liability that the edge of the inner sole or sole will be lifted by engagement with the stretching upper and be crowded back from the edge of the last. In "welt" and "turn" 25 shoes the innersole or sole is provided with a beveled or "feather" edge which as the upper is stretched and drawn inwardly over the last, is particularly apt to be lifted by the same and to be turned or rolled up away from the last.

The object of this invention is to provide means for holding down the edge or the feather edge, as the case may be, according to the class of shoes operated upon and to 35 prevent its being caught by the upper and pulled up or displaced laterally from its proper position.

A special difficulty which it is an object of this invention to overcome is encountered in the manufacture of turn shoes or shoes which are assembled and lasted upon their single soles while these parts are inside out and then turned. The feather of the turn sole over which the upper is lasted 45 is the portion of the sole which projects beyond the inseam after the shoe is turned and in the finished shoe. During the lasting operation this feather necessarily projects more or less beyond the edge of the last 50 so that in lasting turn shoes it is particularly difficult to avoid rolling up and crowd-

ing back this feather. Another special condition prevailing in turn shoe manufacture is that the soles are moist or "in temper" at the lasting stage in order that they may 55 be flexible for the turning operation. This condition adds to the liability of displacing the thin edge of the sole while stretching the upper.

An important feature of this invention 60 consists in combining with upper pulling pincers means for holding down the feather of the sole or innersole at and adjacent to the place where the stretching upper is liable to engage the edge of the feather. 65

It is also a further feature of this invention so to connect the upper pulling means with the described hold-down that the hold-down has a movement or receives a pressure tending to produce movement downwardly 70 in the direction reverse to that in which the upper is being pulled; and it is a further feature of this invention that the hold-down is so operated that it is capable of movement backwardly or inwardly over the feather in 75 time relation with any overdrawing movement which the pincer may have.

The illustrated embodiment of this invention is a hand pincer and the hold-down is carried by the pincer but it is obvious 80 that the broad invention herein disclosed is capable of being applied to machine pincers as well as being embodied in various forms of construction.

A novel invention is disclosed in the illustrated arrangements in which the hold-down comprises a member movably connected with the pincer for engaging the shoe at two points, one point being upon the feather and the other remote from the edge of the 90 sole and the connection permitting transmission downwardly upon the sole of the pressure exerted by the pincers upon the upper. It is a characteristic of this construction that the hold-down has a sliding contact with or 95 abutment against a fixed projection from the pincer which may be the tack driving projection usually found upon hand pincers. In a preferred embodiment of this invention, however, provision is made for moving 100 the hammer backward out of the way as the operation of stretching the upper pro-

gresses so as to allow the pivoted fulcrum or downhold member to bear upon the sole, backward movement of the downhold being prevented in this form, by a separate stationary abutment which may be embraced by the movable hammer in its normal or operative position.

Still another feature of the invention is the provision of means whereby the downward pressure upon the two legs of the downhold member is at first nearly evenly divided and as the stretching of the upper progresses the pressure is transferred from the inner leg, resting on the sole, to the outer leg, resting on the feather. By this means the downward pressure on the feather is increased with the upward pull on the upper.

Figure 1 is a side view of one form of the device; Fig. 2 shows this form of the device in operation near its initial position; Fig. 3 represents in full lines the device of Fig. 2 near its extreme stretching position and in dotted lines the device drawn inward ready for the operation of securing the upper by tacking. Fig. 4 represents a modified form of the device involving the principles exemplified in the first form; Fig. 5 shows the modified form of the device in operation.

The device shown in Fig. 1 of the drawings embodies the usual type of lasting pincers having curved jaws 2, 4, the lever handles 3, 5, and a downwardly projecting member 6 which serves, in the ordinary use of hand pincers, alternately as a fulcrum about which the pincers are operated as a lever by depressing the handles 3, 5 when the upper is gripped and as a hammer head for driving a tack after the upper has been stretched and drawn inward over the last. The present invention is herein shown as embodied in an attachment for this common type of pincer whereby the edge or feather-edge of the sole is positively held down during the upper pulling operation. As illustrated in Fig. 1, this attachment comprises a curved or crescent-shaped downhold member 8 pivotally connected to the lower jaw of the pincers by a pair of links shown as connected and forming an H-shaped member 10. The upper ends of the uprights of the member 10 are pivoted at 12 to the lower jaw of the pincers and the lower ends of the said member to the crescent-shaped downhold member at 14. The rear face 16 of the member 8 bears against the face 18 of the rigid abutment 6 which serves to guide and direct relative movement of the pincers and the sole rest. A spring 20 is provided which bears against the cross bar of the H-shaped member and is seated in a recess in the lower face of the jaw 2, which spring acts to hold the member 8 normally in the posi-

tion shown in Fig. 1 with the point or cusp 22 of the crescent-shaped member 8 in depressed position and against the abutment 18 and the point or cusp 24 of the said member elevated above the end of the pincer jaws. In using this form of the device the upper of the shoe is grasped by the pincer jaws in the usual manner, and the handles thereof depressed so as to bring the cusp 22 of the member 8 in contact with the sole of the shoe. The effect of this is to elevate the cusp 22 and to depress the cusp 24 inside the upper and against the edge or "feather-edge" of the sole, so that upon farther downward movement of the pincer handles a positive pressure is exerted upon the feather-edge of the sole in direct proportion to the upward pull upon the upper. In this manner the elevation of the edge or feather by the movement of the upper there-over is positively prevented. From an inspection of Fig. 3 which shows the parts of the device in their extreme stretching position (in full lines), it will be seen that as the parts advance from the position shown in Fig. 2 to that of Fig. 3 the H-shaped link member and the forward part of the crescent-shaped down-hold 8, which bears the cusp or leg 24, form a toggle joint with the pressure on the cusp 22 tending to straighten the toggle. In the initial position (Fig. 2) the downward pressure on the divided fulcrum is substantially evenly divided between the legs or cusps 22 and 24 but as the stretching advances the pressure is transferred more and more to the leg or cusp 24 and hence the hold-down effect on the feather increases as the tension on the upper increases. When the upper has been sufficiently stretched by bringing the parts to the position of Fig. 3 the device is drawn inwardly to bring the upper over the sole to the position shown in dotted lines in Fig. 3, the feather engaging point or leg of the sole rest member 8 being of course drawn inward at the same time. The operator now holds the upper against the edge of the sole with the thumb of his left hand and with the thumb and forefinger of his right hand, which still holds the pincer handles, inserts a tack through the upper into the sole in the proper place to secure the upper in its stretched and overdrawn position. He then driven the tack with a blow from the hammer head 6 of the pincers. In Figs. 4 and 5 is represented a form of the device in which the cusp 22 of the crescent-shaped sole-edge downhold does not extend normally below the face of the hammer member, as this provision is found desirable in practice. In this form of device, the curved member 8 and the H-shaped member 10 are substantially identical with those of the form already described. In

place of the hammer head shown in Fig. 1, however, there is provided a rigid abutment 6 against which the convex side of the curved member bears and is thereby restrained in its movement longitudinally of the device, the function of this abutment, as far as its relation to the curved member is concerned, being identical with that of the hammer head of the form shown in Fig. 1. For driving the tack there is provided a hammer member 7 pivoted at 26 just back of the base of the rigid abutment 6. During the pulling-over operation this hammer head 7 must be swung out of the way so that the legs or cusps 22 and 24 may act as fulcrums for the pincers. This is accomplished by connecting the head 7 by the links 28 to the end of the member 8 near the cusp 22. The links 28 are arranged one on each side, and are pivoted at one end by the pin 32 to the member 8 and at the other end by the pin 34 to the hammer member 7. By this connection it will be apparent from Figs. 4 and 5 that as the point 22 of the curved member 8 is brought to bear upon the sole of the shoe and is thereby elevated during the stretching of the upper the head 7 will be swung backwardly, as shown in Fig. 5, entirely out of the way of the operation of the curved member 8. When the pulling-over operation has been completed and the pincers are released the parts are brought back to their original position, as shown in Fig. 4, by means of a spring 30 wound about the pivot 26 and one end thereof attached to the head 7 in some suitable manner, as by threading it through the pivot pin 34 of the link 28, and the other end, to the jaw of the pincers, as by threading it through the pivot pin 12. A similar spring is arranged in the same way on the opposite side of the tool. The operation of this form of the device, being substantially the same as that of the form first described, will now be readily understood without further details.

It will be of course understood that the member referred to as the "curved or crescent-shaped member 8" is so named merely for the purpose of identification in the drawing and that this member may be variously shaped and be connected to the pincers in various ways without destroying its function as a sole edge down-hold and as a fulcrum for the hand levers 3 and 5. The provision in hand lasters' pincers of means for positively holding down the feather-edge of a sole during the stretching operation on the upper is believed to be entirely novel and I do not wish, therefore, to be limited to the specific means herein disclosed for accomplishing that object, but

Having explained the purpose and function of my improved device and having shown mechanical embodiments thereof

without attempting to disclose all the forms in which it may be arranged, what I claim as my invention and desire to secure by Letters Patent is:

1. A hand lasting pincer, comprising in combination, crossed levers having the longer arms thereof formed as handles and the shorter arms thereof formed as co-operating jaws, sole edge engaging means operatively associated with the lower jaw of the pincer and between which and said jaw there is relative movement to enable it to engage and to hold down the sole edge during the upper stretching operation.

2. A hand lasting pincer, comprising in combination, crossed levers having co-operating handles on their longer arms and co-operating jaws on their shorter arms, and means acting with continuous pressure on the same portion of the feather edge of the innersole to hold down the same during the upper stretching operation effected by the pincer.

3. A hand lasting pincer, comprising in combination, crossed levers having the longer arms thereof formed as handles and the shorter arms thereof formed as co-operating jaws and a member directly associated with the inner one of the upper pulling jaws and relatively to which the jaws move in pulling the upper in a direction to cause it to press down the feather of the sole with increasing force as the upper is pulled.

4. A hand lasting pincer comprising in combination crossed levers having the longer arms thereof formed as handles and the shorter arms thereof formed as co-operating jaws, means for holding down the sole edge; and means whereby the pressure applied thereto increases faster than the pull on the upper is increased.

5. A hand lasting pincer comprising in combination crossed levers having the longer arms thereof formed as handles and the shorter arms thereof formed as co-operating jaws, means for positively holding down the sole edge during the stretching of the upper, and means whereby the downward pressure on the edge is varied at a rate different from that at which the upward tension on the upper is varied.

6. A hand lasting pincer comprising in combination crossed levers having the longer arms thereof formed as handles and the shorter arms thereof formed as co-operating jaws for straining the upper over the last, a down-hold for the feather edge of the sole; and means whereby, as the upper yields to the strain, the pressure applied to the down-hold approaches in degree the pull on the upper.

7. In a lasting pincer comprising, in combination, crossed levers having co-operating

- handles on their longer arms and coöperating jaws on their shorter arms, a fulcrum member having a sole edge engaging portion arranged in close proximity to the rear face of the lower jaw to engage and hold down the edge of the shoe sole and a separate bearing portion to engage the sole remote from its edge and a pivotal or fulcral connection between said member and said jaws.
10. 8. A hand pincer having upper seizing and pulling jaws, an abutment acting as a fulcrum for the pincer, a hammer projection on the lower side of the pincer which is movable during the use of the pincer to a position away from the abutment to permit close approach of the pincer to the work, and means for automatically returning said projection into operative position toward said abutment.
20. 9. In hand lasting pincers, means whereby the upper may be stretched over the last and sole of a Goodyear welt or turn shoe, means acting on the depressed marginal edge of the sole and operatively connected with the stretching means to receive downward pressure during the stretching operation to force the sole edge down upon the last bottom.
30. 10. In a device of the class described, pincers provided with curved jaws and a rigid abutment, means pivoted to the lower jaw and operatively engaging said rigid abutment and adapted to bear upon the feather edge of a sole and upon a portion of the sole farther from the edge while the pincers engage the upper, whereby pressure is applied to the feather edge as the upper is pulled over by the pincers.
40. 11. In a device of the class described, pincers provided with curved jaws and a rigid abutment located on one jaw inside the curve thereof, a crescent-shaped member, links, pivoted to said member and said jaw whereby the crescent shaped member is supported with one cusp adjacent the jaws and the other cusp adjacent the abutment, and means for normally holding the latter cusp depressed.
50. 12. The combination with lasting pincers, of a fulcrum member pivoted thereto, a pivoted hammer member and means connecting said fulcrum member and said hammer member whereby the latter is swung out of operative position as the pincers pull the upper.
60. 13. The combination with lasting pincers, of a fulcrum member pivoted thereto and having a plurality of fulcrum points, means holding said member against displacement longitudinally of the pincers, a pivoted hammer member and links connecting said fulcrum member and said hammer member whereby the latter is swung out of operative position as one end of the fulcrum member is elevated, and means for returning the

hammer member to operative position when pressure on the fulcrum member is released.

14. The combination with lasting pincers, of a fulcrum member, a pivoted hammer member and means whereby the hammer member is swung out of operative position as the upper is pulled, and means for returning the hammer member to operative position when pressure on the fulcrum member is released.

15. The combination with lasting pincers, of fulcrum means engaging the sole at the edge and elsewhere, and means whereby, as the upper is pulled, fulcral pressure is transferred from one fulcrum engaging point to another.

16. In an apparatus of the class described, jaws to grasp and pull an upper, levers to which the jaws are connected for hand operation, and a fulcrum formed with a face to rest on the depressed marginal edge of the innersole of a welt or the sole of a turn shoe during the upper stretching operation.

17. In an apparatus of the class described, jaws to seize and pull an upper, a sole edge downhold, a link connecting the downhold to one of the jaws and forming with the downhold a toggle, and means coöperating with said parts to effect relative movement in the direction to strengthen the said toggle during the upper pulling operation.

18. In an apparatus of the class described, jaws to seize and pull an upper, a sole edge downhold, a link connecting the downhold to one of the jaws and forming with the downhold a toggle, and means coöperating with the downhold and the jaws to guide and direct relative movement in the direction to straighten said toggle as the upper pulling operation proceeds.

19. In an apparatus of the class described, the jaws 2 and 4 pivotally connected for relative upper seizing movement and having the levers 3 and 5 for effecting upper pulling movement, the hold-down 8, having the legs 22, 24, the link 10 connecting the hold-down to the jaw 2, and the abutment 6 secured to the jaw 2 and engaging the hold-down during the upper stretching operation to guide and direct relative movement of the jaws and the hold-down in the direction to move the link and the leg 24 of the hold-down toward alinement.

20. In an apparatus of the class described, the jaws 2 and 4 pivotally connected for relative upper seizing movement and having the levers 3 and 5 for effecting upper pulling movement, the hold-down 8, having the legs 22, 24, the link 10 connecting the hold-down to the jaw 2, the abutment 6 secured to the jaw 2 and engaging the hold-down during the upper stretching operation to guide and direct relative movement of the jaws and the

hold-down in the direction to move the link and the leg 24 of the hold-down toward alinement, the hammer member pivotally connected to one of the jaws, and the link 28 connecting the hold-down with the hammer member to swing the latter backwardly during the upper pulling movement.

21. In an apparatus of the class described, jaws to seize and pull an upper, a lever to 10 actuate the jaws and toggle members one of which is connected with the jaws and the other of which is adapted to rest on the sole and which are arranged to be moved by the operation of said lever in the direction to 15 straighten them for the pulling operation.

22. In an apparatus of the class described, jaws to seize and pull an upper, a lever to actuate the jaws, a sole rest having a portion arranged to engage the sole remote from its 20 edge and a portion which is arranged to engage the sole adjacent to its edge and to form a toggle member, a link pivotally connected to said member and to the upper pulling means and forming a second toggle 25 member, and an abutment on the upper pulling means which has sliding engagement with the rear portion of the sole rest to control movement in a path to straighten the toggle members.

30 23. In an upper pulling apparatus, a pincer comprising coöperating jaws and operating hand levers, a sole rest formed to engage the feather of a sole and to overlie the shoulder and engage the sole back of the 35 feather and upon which the pincers are fulcrumed, and means for maintaining normal pivotal relation of the sole rest and the pincers.

24. In an upper pulling apparatus a pincer comprising jaws and an operating lever, a sole rest formed to engage the feather of a sole and to overlie the shoulder and engage the sole back of the feather and a link forming a movable fulcrum for the pincer and 45 connecting the pincer to the sole rest.

25. In an upper pulling apparatus, a pincer, a hold-down formed and arranged to

engage the feather of a sole, and a connection between the pincer and the hold-down to cause the pincer to be moved backwardly 50 from the edge of the sole during overdrawing movement of the pincer.

26. In an upper pulling apparatus a pincer, a hold-down formed and arranged to engage the feather of a sole, said parts being 55 connected to allow the pincer to have a combined upper stretching and initial overdrawing movement while the hold-down prevents displacement of the sole edge and then to permit the hold-down to be moved inwardly 60 from the edge of the sole with the pincer when the latter is manipulated to lay the upper down upon the sole.

27. A hand pincer having upper seizing and pulling jaws, a sole rest and a hammer projection which is automatically moved 65 from operative position during the upper pulling operation and returned after that operation.

28. A hand pincer having upper seizing 70 and pulling jaws, an abutment and a hammer projection on the lower side of the pincer which are movable relatively during use of the pincer toward and from positions to permit close approach of the pincer to the 75 shoe bottom.

29. An apparatus of the class described, having in combination, upper pulling jaws and a hold-down which rests on the feather of the sole during the upper stretching operation and drags inwardly over the feather in advance of the upper during the overdrawing operation, and means by which the pincers may be operated independently of the hold-down, as and for the purpose de- 80 scribed.

In testimony whereof I have signed my name to this specification in the presence of two subscribing witnesses.

JOHN EMERSON SCOTT.
